UNITED STATES PATENT OFFICE.

ARTHUR JOHN HALL, OF WINCHCOMBE, ENGLAND, AND PAUL L. MARDIS, OF SWISS-VALE, PENNSYLVANIA, ASSIGNORS TO WESTINGHOUSE ELECTRIC AND MANUFACTURING COMPANY, A CORPORATION OF PENNSYLVANIA.

SWITCH MECHANISM.

Application filed January 31, 1921. Serial No. 441,412.

To all whom it may concern:

Be it known that we, ARTHUR J. HALL, a subject of the King of Great Britain, and a resident of Winchcombe, England, and

5 PAUL L. MARDIS, a citizen of the United States, and a resident of Swissvale, in the county of Allegheny and State of Pennsylvania, have invented a new and useful Improvement in Switch Mechanism, of which

10 the following is a specification.

Our invention relates to switch mechanism and particularly to switch mechanism for controlling a plurality of motor circuits.

15 One object of our invention is to provide a switch for use in controlling motor circuits, wherein a control switch for an electrically operated switch is so interlocked with a disconnecting switch that the latter cannot be

20 opened while the former is in closed position.

Another object of our invention is to provide a switch mechanism having the above characteristics, wherein the control switch 25 is carried by a protecting cover that serves to protect the disconnecting switch when the control switch is in closed position.

A further object of our invention is to provide a switch mechanism having the above 30 characteristics, wherein a main line switch is so interlocked with the control switches that the latter cannot be opened so long as the main switch is in closed position.

These and other objects that will be made 35 apparent throughout the further description of the invention are attained by means of the apparatus hereinafter described and illustrated in the accompanying drawings, wherein:

40 Figure 1 is a front plan view, showing a portion of one of the switch protecting covers broken away;

Fig. 2 is a sectional view of the switch mechanism taken on the line II-II of Fig. 45 1 looking in the direction of the arrows and showing the switch mechanism in side elevation; and

50 Fig. 3 is an end elevational view of the switch mechanism, a portion of one of the protecting covers being broken away.

Referring to the drawings, the apparatus includes an insulating base member 4 upon which are mounted four disconnecting or auxiliary switches, each of which includes a

55 pivot jaw member 5, a switch blade member 6 that is pivoted to the pivot jaw member by means of a bolt 7, and a contact jaw member 8 that is adapted to receive the free end of the switch blade member. The free end of the blade member is provided with 60 an opening 9 for the purpose of receiving the hook of an operating tool commonly known as a "hook stick."

The jaw members 5 and 8 are provided with terminal members 10 which project 65 through the insulating base and are connected to a motor circuit. Each disconnecting switch controls a separate motor circuit which also includes an electrically connected unit switch for the purpose of interrupting 70 the circuit through the motor and through the disconnecting switch before the latter is opened.

The mechanism is therefore provided with 75 a separate controlling switch for controlling the operation of each unit switch. Each controlling switch comprises a pair of contact jaw members 11 that are mounted upon the base 4 on opposite sides of the disconnecting switch blades 6.

80 An insulating cover 12 having sufficient length and width to substantially cover the disconnecting switch members is provided for each disconnecting switch and is pivoted by means of a hinge 13 that is mounted upon an insulating block 14 which is secured to the panel 4. A bridging switch blade member of U-shape having two switch blade members 15 is secured to the inner side of the cover 12 and engages the contact jaw members 11 when the cover is in operative protecting 85 position, indicated in the drawings.

90 The contact members 11 and the switch blade members 15, when in operative relation, establish a circuit through the unit switch actuating mechanism. It will be apparent, therefore, that when the cover is pulled away from the blade member 6 to permit opening movement thereof, that the circuit through the unit switch mechanism 95 is first interrupted, thus interrupting the circuit through the disconnecting switch. The disconnecting switch may then be operated without danger of injury to the operator.

100 The inner side of each cover 12 is provided with an insulating block 16 that engages the free ends of the contact jaw mem-

bers 8 when in closed position. The covers are releasably retained in closed position by reason of the engagement of the switch blade members 15 with the yielding contact 5 jaw members 11. The exterior side of each cover is provided with a loop member 17 for the purpose of receiving a "hook stick" by means of which the covers may be moved to open position.

10 It will be seen from the foregoing that in order to operate the disconnecting switches 6, it is first necessary to move the covers 12 to open position. The covers are mounted for independent movement and any 15 one of them or all of them may be opened or closed without interfering with another.

10 In electrical systems wherein a plurality of motors are operated, it is frequently the practice to control the main circuit supplying current to the motors with a main or line switch. It is an object of this invention to so interlock the main switch with the switches controlling the actuating mechanism of the unit switches controlling the 20 motor circuits, that the latter cannot be opened so long as the main disconnecting switch is in closed position. With this end in view, the main line disconnecting switch is provided with means whereby opening 25 movement of the covers 12 is prevented so long as the switch is in closed position.

35 The main line switch includes a pair of switch blade members 18 that are pivoted upon jaw members 19 and which are adapted to be moved into engagement with a pair of contact jaw members 21 that are mounted upon a block 22 that is secured to the base member 4. The pivot jaw members are mounted upon a block 23 that is similar 40 in every respect to the block 22.

45 The switch blade members 18 are connected by an insulating bar 24 to which is attached an insulating rod 25. The rod 25 extends over the covers 12 that are disposed on opposite sides of the main switch. When the main switch is in closed position, the rod 25 engages the outer faces of the covers 12 and prevents opening movement thereof. The main switch is provided 50 with an eye bolt 26 for the purpose of receiving the hook member of a "hook stick" by means of which the main operating switch is actuated. It will be apparent from the foregoing that the cover members 12 carrying the controlling switch blade 15 55 cannot be moved to open position so long as the main switch is in closed position.

60 By the arrangement of interlocks above described, it will be apparent that the motor circuit disconnecting switches are twice guarded, first by the main switch interlock and second by the control switch interlock.

65 The construction is extremely simple and inexpensive and the switch mechanism may

be applied to a variety of applications wherein it is desirable to insure that the switch mechanism shall be disconnected from a source of voltage before the manually operated switch mechanism is made accessible. The 70 invention is, therefore, not limited to the specific application referred to in connection with the description of the apparatus.

75 While we have described and illustrated but one embodiment of our invention, it will be apparent to those skilled in the art that various changes, modifications, substitutions, additions and omissions may be made in the apparatus illustrated without departing from the spirit and scope of the 80 invention, as set forth in the appended claims.

We claim as our invention:

1. Switch mechanism comprising an insulating panel, a switch member mounted on the panel, a pair of contact members, an insulating cover pivoted upon the panel and movable independently of the switch member for protecting the switch member, and a switch member carried by the cover for connecting the pair of contact members. 85

90 2. Switch mechanism comprising an insulating panel, a switch member mounted on the panel, an insulating cover pivoted upon the panel for protecting the switch mechanism, contact jaw members mounted on the base and a switch member carried by the cover for connecting the contact members and having frictional engagement therewith whereby the cover is yieldingly retained in 95 operative relation with the switch member. 100

95 3. Switch mechanism comprising a plurality of switch members, a separately movable cover for each switch member movable independently of the switch member, a main switch and means carried thereby for preventing opening movement of the covers so long as the main switch is in closed position and a separate switch connected to and operable by each door for controlling the circuit through the first said switch member. 105

110 4. Switch mechanism comprising a disconnecting switch, a cover for the disconnecting switch movable independently thereof for preventing opening movement of the disconnecting switch so long as the cover is in closed position, and a switch for controlling current through the disconnecting switch carried by the said cover and movable therewith into open and into closed 115 positions. 120

125 5. Switch mechanism comprising a base member, a disconnecting switch mounted on the base member, a cover for the disconnecting switch movable independently thereof for preventing opening movement of the disconnecting switch while the cover is in closed position, a pair of switch contact members mounted on the base and a bridging switch member carried by and movable 130

with the cover for connecting the said switch contact members when the cover is in closed position and adapted to be disengaged from the contact members when the cover is in 5 open position.

6. Switch mechanism comprising a base member, a disconnecting switch mounted on the base member, a cover for the disconnecting switch movable independently thereof for preventing opening movement of the disconnecting switch while the cover is in closed position, a pair of switch contact members mounted on the base and a bridging switch member carried by and movable 10 with the cover for connecting the said switch contact members when the cover is in closed position and adapted to be disengaged from the contact members when the cover is in open position, the said bridging switch being adapted to control the current 15 through the disconnecting switch.

7. Switch mechanism comprising a base member, a disconnecting switch mounted on the base member, a cover for the disconnect-

ing switch movable independently thereof 25 for preventing opening movement of the disconnecting switch while the cover is in closed position, a pair of switch contact members mounted on the base, a bridging switch member carried by and movable with 30 the cover for connecting the said switch contact members when the cover is in closed position and adapted to be disengaged from the contact members when the cover is in open position, and a switch movable independently of the disconnecting switch and cover having a means thereon extending over the cover for preventing opening movement of the cover so long as the last said switch 35 is in closed position.

In testimony whereof, I, ARTHUR J. HALL, have hereunto subscribed my name this 13th day of December, 1920.

ARTHUR JOHN HALL.

In testimony whereof, I, PAUL L. MARDIS, 45 have hereunto subscribed my name this 19th day of January, 1921.

PAUL L. MARDIS.
